[57] CLAIM

The ornamental design for a contoured beach pillow, as shown and described.

DESCRIPTION

FIG. 1 is a top, rear, and left side perspective view of a contoured beach pillow showing my new design; FIG. 2 is a top, front, and right side perspective view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear elevational view thereof; and

FIG. 8 is a front elevational view thereof.

The handle element is shown in a retracted position in FIGS. 3, 5 and 6.

FIG. 1
